UNITED STATES PATENT OFFICE.

MICHAEL MARY BROPHY, OF LONDON, ENGLAND.

SHOCK-ABSORBER FOR VEHICLES.

1,052,795.

Specification of Letters Patent. Patented Feb. 11, 1913.

Application filed January 3, 1911. Serial No. 600,605.

To all whom it may concern:

Be it known that I, MICHAEL MARY BROPHY, a subject of the King of Great Britain, residing at 48 Gordon Square, London, England, have invented new and useful Improvements in Shock-Absorbers for Vehicles, of which the following is a specification.

My invention relates to means or apparatus for mounting two bodies or parts of a body in such relation to each other that shocks or vibrations imparted to one of such bodies or parts of a body will be communicated to the other in lesser degree, and to that class of such apparatus wherein the body to be protected from vibration is carried by a lever or levers arranged in conjunction with a spring or springs for affording the necessary resistance.

According to my invention which is applicable to all kinds of vehicles such, for example, as motor road vehicles, cycles, railway locomotives and carriages, horse drawn vehicles and baby carriages and seats, or chairs, couches and the like, carried by such vehicles and also on board ship, the lever or system of levers for supporting the body which is to be protected against the effect of vibration is or are arranged in such relation to the spring or springs, which under the vibrations are compressed or put into tension, that the effective length of the lever supporting the body is increased while the effective length of the lever acting against or upon the spring is decreased in the same ratio as the compression or extension of the latter is increased, and vice versa.

To enable my invention to be fully understood, I will describe the same by reference to the accompanying drawings, in 40 which;

Figure 1 is a diagrammatic view illustrating the principle of my invention. Fig. 2 shows the application of my invention to a construction embodying a single plate spring. Fig. 3 is a view of a like construction in which the links are connected to the lever so as to be adjustable toward or from each other. Fig. 4 is a view showing the application of my principle to a vehicle 50 having the body connected to a C-shaped bracket. Fig. 5 is a view of the application of my invention to steady a platform. Fig. 6 is a detail of the construction shown in Fig. 5. Fig. 7 is a diagrammatic view of 55 an arrangement of levers applied to steady a platform and a second platform mounted

thereon. Fig. 8 is a side view of a berth or couch with my invention applied thereto. Fig. 9 is a plan view of the lever and connection employed in the modification shown 60 in Fig. 8, and Fig. 10 is a sectional view illustrating a detail of this latter construction.

The principle of my invention will be best understood by reference to Fig. 1, which is 65 a diagrammatic view, A indicating a weight to be supported, B the lever carrying the said weight, and which is assumed to turn about a virtual pivot B', and C, C two springs which are put more or less into compression under the action of the said weight, the said springs being respectively connected to the lever B at the points D, D' on opposite sides of the pivot B'. 70

In the position of the parts shown, the 75 lever B will have an effective length as represented by the line x while it will act upon the springs C, C with a leverage the length of which is represented by the lines y, y. If now the weight A is increased so as to 80 compress the springs C, C to a greater extent, the effect will be to increase the length of the lever B, as represented by the line x', and to shorten the leverage acting against the springs, as represented by the line y', y', 85 whereby the increased resistance which the springs will offer to compression is balanced by the increase on the one hand of the length of the leverage between the fulcrum and the load, and the shortening of the leverage between the fulcrum and the point of application of the power. As hereinbefore stated this principle can be very advantageously applied to motor vehicles, its 90 application permitting of such a vehicle running with equal steadiness whether lightly 95 or heavily loaded.

Fig. 2 shows the application of the invention in connection with an elliptical or plate spring. In this arrangement the lever 100 c will turn more or less around the point h, the said lever being connected by links i, i to the chassis and to the spring e so that the effect of the movements of the axle b relatively with the chassis will produce a result 105 very similar to that described with reference to the diagrammatic view, Fig. 1.

In Fig. 3 the arrangement is substantially the same as that shown in Fig. 2, except that the lever c is provided with right 110 and left hand screw-threads and the links i, i are connected to nuts j, j on the said

screw-threaded portions so that by rotating the screw-lever an adjustment can be effected according to the weight of the vehicle or the power of the spring. To allow of the rotation of the said lever it will be noticed that the end connected to the axle is formed with a ball which works in a socket *k*.

Fig. 4 shows an application of the invention to a vehicle having the body mounted on C-brackets in this case, the lever *c* is connected to the body of the vehicle by means of a ball and socket joint, as in the arrangement last described, the said lever being also provided with right and left hand screw-threads upon which nuts *j*, *j* are mounted; the springs *e*, *e* are connected to these nuts and to the C-bracket and under the weight of the body of the vehicle both these springs are placed in tension, the lever moving on an imaginary pivot, between the two springs so that under any variation of the weight of the body the distance between the points of connection of the said springs, to the lever *c* will be decreased and the leverage correspondingly increased in the manner hereinbefore described.

Fig. 5 represents the application of my invention to a floating platform which might be very advantageously employed where great steadiness is required, for instance, for conducting philosophical or scientific experiments. The platform which is indicated by the letter *l* would be carried on, say four levers, two at each end, each lever being carried by two springs *e*, *e* as described in the last modification. The nuts *j*, *j* shown in this figure are arranged to slide in a slot in the lever *c* by means of a screw *j'* having right and left hand threads, as clearly shown in Fig. 6, which is a section on the line 9—9 Fig. 5; the adjustment of the said nuts by means of the screw can be effected through the medium of bevel gearing as at *m*, the gear wheels in connection with the several levers being operated simultaneously through the medium of suitably arranged shafts such as *n* which are geared not only to the adjusting screws, but to each other. If still greater protection is desired against vibration than that provided for by the arrangement shown in Fig. 5, the platform *l* might have mounted upon it a second platform *n* mounted similarly to the platform *l* as indicated in Fig. 7.

Figs. 8 and 9 illustrate the application of my invention to a berth or couch, Fig. 8 being a side elevation, and Fig. 9 a sectional plan. As represented in these figures the berth is supported upon two pairs of levers, *o*, *o* mounted upon spindles *p*, *p* carried in suitable bearings on a frame *q* and these spindles *p*, *p* have upon them quadrants *v*, *v* which are connected by a chain *r'* in the manner indicated so as to insure the two

ends of the berth rising and falling in unison. The spring lever *c*, by means of which the weight of the berth is directly carried is arranged to move horizontally over the frame *q*, the said lever having in connection with it springs *e*, *e* and being connected at one end by a ball and socket joint *s*, shown drawn to an enlarged scale in Fig. 10, to a quadrant *t* through the medium of a chain *u*, the rising and falling movement of the berth being thus communicated to the spring lever *c* which oscillates about an imaginary pivot between the nuts to which the two springs are connected, substantially as hereinbefore described. It will be obvious that the arrangement illustrated in Figs. 8 and 9 is equally applicable to a seat or chair.

In all of the figures of the drawings where the lever is not formed with one portion at an angle to the other the connections of the links therewith are made in such manner as to enable me to secure the same result. It will be observed that in all of these cases, the forward side of the lever makes a smaller angle with the line of load pressure than the like angle of a line connecting the point of attachment of the links thereto, and that by this arrangement under the varying conditions of use the points at which the links are connected to the lever will approach and recede from a line connecting the points at which the opposite ends of the links are secured.

In the foregoing description springs are, in a part of the construction, used as links and in another part rigid links so connected with a spring or springs as to yield under load pressure, are employed. It is to be considered that these parts are variations of the same feature of construction and are generically considered equivalents and that all are elastic.

Having now particularly described and ascertained the nature of my said invention and in what manner the same is to be performed, I declare that what I claim is:

1. A shock absorbing device comprising a lever to one end of which the weight or body to be protected from shocks is connected, and two links carrying the said lever without the employment of any fixed pivot, the said links being arranged in such relation to each other that the pivotal points of connection to the lever approach and recede from a line connecting the pivotal points at the outer ends of the links during an oscillation of the said lever, substantially as described.

2. A shock absorbing device comprising a lever, to the free end of which the load is to be connected, two links elastically connecting two supports with two separated points on opposite sides of the lever, the angle formed by the forward side of the lever to

the line of load pressure or draft being less than the like angle formed by a line passing through the points of the link attachment thereto.

- 5 3. In a shock absorbing device, the combination with a lever, one end of which is to be connected with the load, of two elastic supports for said lever connected to the said lever near the opposite end of the same, said 10 points of connection with said lever being on opposite sides of the lever at a distance apart, and means for adjusting said points of connection toward and from each other.
4. In a shock absorbing device, the com-

bination with a lever, one end of which is to be connected with the load, of two elastic supports for said lever near the opposite end of the same, said points of connection being on opposite sides of the lever near the opposite end of the same, and engaging 20 right and left hand threads upon said lever for adjusting the said points of connection toward and from each other.

MICHAEL MARY BROPHY.
